UNITED STATES PATENT OFFICE.

JOSEPH CHMIELEWSKI, OF CLEVELAND, OHIO.

AEROPLANE.

1,125,652.

Specification of Letters Patent.

Patented Jan. 19, 1915.

Application filed July 21, 1913. Serial No. 780,201.

To all whom it may concern:

Be it known that I, JOSEPH CHMIELEWSKI, citizen of the United States, residing at Cleveland, in the county of Cuyahoga and State of Ohio, have invented certain new and useful Improvements in Aeroplanes, of which the following is a specification.

This invention relates to an aerial machine, all substantially as shown and described and particularly pointed out in the claims.

In the accompanying drawings, Figure 1 is a perspective front view of the machine, and Fig. 2 is a perspective rear view thereof. Fig. 3 is a plan view. Fig. 4 is a side elevation, and Fig. 5 is a longitudinal sectional elevation. Fig. 6 is a transverse cross section. Fig. 7 is a side elevation of one of the propelling blades, and Fig. 8 is a plan or edge view thereof. Figs. 9 and 10 are cross sections on lines 9 and 10, respectively, Fig. 8.

The invention as thus shown belongs to one of the larger types of aerial machines or fliers and requires approximately a hundred and fifty horse power engine or motive power to propel the same through the air. The frame work, represented generally by *f*, may be of any suitable material and built on the lines shown, the essential principles of construction being observed, and provides a three deck machine as seen at 1, 2 and 3 successively from bottom to top. The lower deck in fact is erected upon two boats *b* as its base, which are built together as one by the frame work *f* of the machine which connects them in a rigid structure. The engines *E* are located in these side members or boats or in the holds thereof and are covered in beneath the deck, as seen in Fig. 6, where they are entirely out of the way and housed against all unfavorable conditions of weather and from possible untoward air currents or disturbances. Power is taken off the said engines by means of belts or chains 5 or their equivalent running on counter shaft 4, and belts or sprocket chains 6 convey the power thence to the propeller shafts 7. The propellers *P* are hereinafter fully described and two or more may be employed on each side of the machine, fore and aft, respectively, or there may also be an intermediate propeller as shown in Fig. 4. The shaft 4 runs back to the rear of the machine 55 as also does the engine shaft beneath, and chains or belts 6 are provided at both ends

of said shafts, in this instance, to convey the power to the propeller blades. The boat also has rollers or wheels *w* at the front and at the rear upon which it is adapted to run 60 or ride on land, and these wheels may be swung rearward and out of contact relations when they are not used or the boat takes to the water.

The machine is perfectly balanced upon its boat bottom and extends laterally in respect to said bottom at either side fully the width of the boat and has said sides relatively above the boat and where they cannot dip in the water nor necessarily get wet 70 when the boat is afloat upon the water. In that case the propellers *P* might be required to propel the boat in the water. Having reference again to the main frame and the two decks 2 and 3, it is to be further observed that the machine as thus constructed 75 is a double bi-plane, with practically distinct front and rear members or portions but having said members or front and rear portions connected by continuous plane surfaces *m* at the middle. The middle propeller blades *P* come centrally between the said two members in the open space at each side, where they are exposed at the top and bottom and free to do their work, and the 80 reversing blades 8 are positioned at both sides in the edges of these open spaces, front and rear, and adapted to reverse the machine as against the action of the forward conveying blades or propellers *P*. The said 85 reversing blades likewise derive their power through suitable connections with the engines *E*, and have force enough to reverse the machine against the action of the blades *P* when under power. The said planes 2 90 and 3, front and rear, are rigidly connected by suitable posts, stays and braces or any preferred material for lightness and strength, whether solid or hollow, and wire stays especially are employed as shown and 95 as is now common in this art. The said planes 2 and 3 are built rigidly into the frame work of the machine by the foregoing means and the propellers *P* have their axis in substantially the same plane as plane 100 or deck 2, and each has its own shaft supported in suitable bearings in frame *f* and driven by sprocket chain or belt 6 from the engine driven counter shaft 4 as above described. The latter shaft is located above 105 the deck of the boat and a wire guard *g* of suitable strength and elevation affords pro-

tection to the persons about said deck. Other guards or fences g^2 and g^3 are provided about the middle portions of the decks or planes 2 and 3 and stairways w' afford passage from one plane to the other.

Both the front and the rear sections or members of the complete machine have ailerons or guide plates a pivotally mounted at their front and bottom beneath the lower planes 2 and 3 and provided with controlling racks r and pinions 10 to govern their position in respect to a horizontal plane, and the said pinions or gears are under the more or less immediate control by the operator 15 of the machine through suitably arranged hand mechanism. The turning or deviation of the machine in flight is determined mainly by the said ailerons or planes, while the plane of flight is governed by the elevators E' at the front of the machine. The said elevators, so-called, or devices for governing the elevation of the machine in flight, have a suitable rudder 12 and are under the immediate control of the aviator 20 through suitable mechanism so as to throw the same into one plane or another according as the machine is to rise or descend or fly on a level. The rudder 12 is mounted for lateral pivoted movement and cooperates with the ailerons above described in 25 directing the machine into other than direct lines of travel. Suitable ropes or cables 15 over pulleys 16 and 17, or their equivalents, control the said elevator.

Suitable rudders R are provided at the rear of the machine, and these are of a butterfly style or build, as seen in Figs. 2 and 3, wherein they are shown as standing normally at an angle of approximately 45 degrees to the axial line of the machine but of course subject to movement laterally both in respect to such line or the line of travel by means of suitable tackle and devices within the control of the aviator, who 40 usually occupies a position behind or within the transparent housing h which incloses the cabin c of the machine. The said rudders may be operated together or separately, and the said wings or rudders have means 45 for operating them extending therefrom to the operator's seat behind or within the transparent housing h , as shown, the said operating means comprising the parts indicated by m' and n and those directly connected therewith. Obviously any equivalent and sufficient means for operating the said rudders may be employed.

The four blade retarding propellers 8 on each side of the machine in addition to their 50 function as retarders serve the important office of maintaining equilibrium when not in full flight. They also are useful in starting to promote an upward or rising movement because they are constructed and arranged to retard forward travel while they

assist in an upward movement of the machine. The short shafts carrying the propellers P are provided with ball bearings to cause them to operate with the minimum of friction.

Referring now particularly to Figs. 7 to 10, it will be seen that the blades of the propellers P have a straight and rather sharp initial edge 20 and a curved rear edge 21, and that between these edges the blade 75 takes on a spoon shape, particularly in its outer larger or end portion, where it curves up rather sharply from the back to the front of the blade. This construction makes the said blades exceptionally effective as propellers on account of the extra deep dip they take on the air, which contributes materially to the buoyancy of the machine. The cabin c is located between the lower or boat deck and the middle deck 2, and the central rigid 85 frame portion f rises from the boat deck to the top of the machine and has the sides which carry the propellers and other working parts built rigidly thereon or therewith and constituting what practically amount to 90 wings with dual planes 2 and 3 at different elevations. The said wings, so-called, also are wholly outside of the sides of said boats and relatively above the plane thereof and of the cabin c , so that when the boats are 95 floating in water the machinery driven by the engines therein is wholly above the water line as also are the propellers P and the cabin c .

What I claim is:

1. An aerial machine of the double biplane type having a pair of boats in its bottom and wing portions at its sides divided into front and rear portions, propeller and retarding blades respectively located in the space between said front and rear portions and a source of power in said boats operatively connected with said blades.

2. An aerial machine having a plurality of boats built into the bottom thereof, power engines in the holds of said boats, a cabin relatively between and above said boats and wings having front and rear portions relatively above said cabin and propellers intermediate of said wings in power relation with 110 said engines.

3. An aerial machine having a pair of boats in its bottom and a cabin built onto said boats and relatively between the same, a frame work extending laterally from the said boats above said cabin on both sides thereof and having wings having the propelling mechanism located thereon, said mechanism comprising two series of propeller blades and retarding blades intermediate of said propellers.

4. An aerial machine having boats built into its base and the body thereof having its sides relatively above the plane of the said boats and extending laterally each side of 125

said boats, a cabin located centrally above
said boats and between the same and beneath
the plane of the said body, propeller blades
mounted in the sides of said body, between
5 the front and rear portions thereof and en-
gines in power relation with said propellers.

In testimony whereof I affix my signature
in presence of two witnesses.

JOSEPH CHMIELEWSKI.
